UNITED STATES PATENT OFFICE.

JAMES A. FLEMING, OF GLOBE, ARIZONA TERRITORY.

APPARATUS FOR LEACHING ORES.

SPECIFICATION forming part of Letters Patent No. 660,498, dated October 23, 1900.

Application filed March 29, 1899. Serial No. 710,934. (No model.)

To all whom it may concern:

Be it known that I, JAMES A. FLEMING, residing at Globe, in the county of Gila and Territory of Arizona, have made certain new and useful Improvements in Leaching Ores, of which the following is a specification.

My invention is an improvement in processes of and apparatus for leaching valuable minerals—such as gold, silver, and copper—out of ore by liquid chemicals or solution of different kinds; and the invention consists in the process and construction and combination of parts, as will be hereinafter described, and pointed out in the claims.

15 In the drawings, Figure 1 is a vertical section of an apparatus embodying my invention. Fig. 2 is a top plan view thereof. Fig. 3 is a sectional plan view drawn above the conical hopper-plate, one-half of such plate being broken away to show the underlying perforated plate for retaining the porous filtering or leaching material; and Fig. 4 is a detail perspective view showing portions of the upper and lower plates of the hopper and 25 of one of the bars for supporting the sections of the lower plate.

In the leaching of ores the solutions, which may be those usually employed, percolate down through the pulverized ores and carry 30 the gold or other metal out of the ore in solution, which is subsequently extracted.

By my invention I seek to provide improvements in the tank or holder, in the means for introducing the solution and for withdrawing 35 the solution, and for compressing the pulp prior to its discharge, together with other improvements, as will be more fully described.

The tank A may be upright, as shown, or inclined so the pulverized ore will feed down 40 therein by gravity. It has an air-tight top provided with an opening or openings A', suitably closed, and which may serve as manholes and for the introduction of the pulverized ore. It also has two nipples B, which 45 may be valved, as shown, and connect with suitable pipes for the introduction and withdrawal of the chemical solution and water. I also provide the top with an opening surrounded by a stuffing-box B', through which 50 is passed the pipe C, which is employed for inserting and withdrawing chemicals. This

pipe C is movable up and down, so it can be adjusted to withdraw or introduce the solution at any desired point in the mass of pulverized ore. Alongside the tank at different 55 heights I provide nipples D, D', and D'' for the introduction and withdrawal of air, chemicals, water, &c.

By the described construction it is evident that the solution may be introduced and withdrawn from the top of the pulverized ore from the interior thereof at any height desired or from the exterior of the mass of ore at any desired height or can be introduced from above or below the top of the mass or from 65 its interior or exterior and withdrawn at any other desired point, thus insuring a proper subjection of each portion of the mass of the ore to the solution and the thorough circulation of the solution through such mass. 70

Within the tank I provide the conical hopper or diaphragm E, the tank being extended below said hopper to form the air-chamber F.

The hopper E has the upper perforated plate G and the lower perforated plate H. The 75 plate G has perforations g, which incline downward toward the inner upper surface of the plate and prevent such perforations from becoming filled by the pulverized ores. At the same time these perforations permit the passage of the solution when desired. The plate H is also perforated and is spaced apart from the plate G, the intermediate space containing a porous leaching-filling, such as charcoal or other suitable material. 80

The lower plate H is made so it can be removed and inserted at will, being preferably made in sections H', supported upon bars H'' and suitably secured so the sections H' can be removed for any desired purpose. 90

The plate H is perforated at h. The chamber F is an air-chamber and a solution-box into which the solution drains from the ore above and may be drawn off at f.

To regulate the flow of solution into the 95 chamber F, I admit air from a blower I or other suitable source of supply to the said chamber and regulate the pressure to secure the desired flow of solution from the pulverized ore. This air-pressure may also operate 100 when considerable pressure is employed to agitate the pulp above the conical hopper and

so secure a proper discharge of the pulverized ore and avoid any clogging of such ore within the tank.

The leached or practically-finished pulp 5 passes by its own gravity from the hopper through the tube J into the barrel K. This barrel K has the contracted discharge K', out of which the pulp is forced by the plunger L, which may be reciprocated by any desired 10 mechanism.

The barrel K, in advance of the tube J, is provided with the perforations J', inclined to avoid clogging, such perforations extending to the contracted end of the barrel. A re- 15 movable perforated base-plate M extends beneath the perforated portion of the barrel and is spaced apart therefrom, forming a chamber M', which receives a filling of porous filtering or leaching material, such as charcoal, hemp, 20 asbestos, or the like. The contracted end of the barrel may be supplied with movable bushings adapted to bring it to any desired size, or an automatic outfeeding device may be built on this end of the plunger-barrel, if de- 25 sired. As the pulp or leached ore feeds down, the plunger, which works through a stuffing-box, advances and compresses the pulp, causing the moisture or solution remaining therein to pass out through the perforations in the 30 barrel. As the plunger advances farther it compresses the finished pulp almost dry in the tapered end of the barrel. The plunger can be operated backward or forward or, if desired, up and down by compressed air, 35 steam, hydraulic, or other power. The well N, leading down from the barrel, can also be used for discharging when desired.

Steam may be introduced through any of the pipes or nipples to heat the ore to any degree desired during the operation of the apparatus.

By the process the ore is subjected to the action of the solution and is subsequently put under pressure for the purpose of removing 45 the surplus solution. The tank being steam and air tight permits the economical use of steam and hot air for heating the ore and also prevents the loss of that heat which results from the admixture of water and sulfuric acid 50 when such a solution is employed. The continuous operation prevents the settling or puddling of the fine particles of the ore, and thus enables the solution to freely circulate or percolate through the same.

55 The air-chamber below the diaphragm is provided with a suitably-closed manhole i, through which the operator may enter the air-chamber for any purpose desired.

Having thus described my invention, what 60 I claim as new, and desire to secure by Letters Patent, is—

1. In an apparatus for use in leaching ores the tank having nipples alongside and communicating with it at different heights, and a 65 tube introduced through its top and movable up and down whereby it may be adjusted to different heights, and said tank having, at its

top, nipples for the introduction of and withdrawal of chemicals all substantially as described whereby the solution may be introduced or withdrawn above the mass of ore or from any height at the interior or exterior of such mass of ore substantially as set forth. 70

2. An apparatus comprising a tank having an inlet and a discharge so the ore may pass 75 in operation through the apparatus and means for compressing the pulp whereby to remove the surplus solution therefrom and means for withdrawing the main portion of the solution in advance of the compressing means sub- 80 stantially as set forth.

3. An apparatus substantially as described comprising the air and steam tight tank having a perforated diaphragm and an air-chamber below the same and means for introducing air under pressure into said chamber the tank being permanently closed at its top during the introduction of the air-pressure into said chamber substantially as set forth. 85

4. An apparatus for use in extracting metal 90 from ore comprising the tank adapted to contain the pulverized ore, means for introducing and withdrawing the treating solutions at different heights through the side of the tank and a pipe inserted from without into 95 the tank and movable vertically at its inner end whereby its said end may be set to different levels within the tank substantially as set forth.

5. In an apparatus, substantially as de- 100 scribed, the combination of the air and steam tight tank having a perforated filtering-hopper having a central pulp-discharge and provided below the hopper and surrounding said pulp-discharge with an air-chamber, means 105 for controlling the discharge of the pulp, and devices whereby to establish air-pressure in the air-chamber, the tank being constructed to be permanently closed above the hopper during the introduction of pressure to the 110 chamber below the hopper substantially as set forth.

6. In an apparatus for extracting metal 115 from ores the tank provided with the closed top having the stuffing-box and the nipple or nipples, the nipples arranged at different heights along its side, the pipe movable longitudinally through the stuffing-box, and the 120 perforated diaphragm substantially as set forth.

7. In an apparatus substantially as de- 125 scribed the combination of the tank having the perforated diaphragm, and an air-chamber below the same, and an air-compressor by which to establish air-pressure in said chamber substantially as set forth.

8. An apparatus for extracting metal comprising the tank having a pulp-discharge and the perforated diaphragm and the air-chamber below the same, the perforated discharge-barrel connected with the pulp-discharge of the tank and having the contracted end, and the plunger operating in said barrel substantially as set forth. 130

9. In an apparatus substantially as described the discharge-barrel having perforations inclining rearwardly toward their outer ends as described and having the removable 5 perforated underlying plate and the filling between said plates, and the plunger operating in the said barrel substantially as set forth.
10. An apparatus substantially as described 10 comprising the tank having the closed top, the stuffing-box, the pipe movable longitudinally through such stuffing-box whereby it may be adjusted within the tank, the nipples arranged at different heights along the side 15 of the tank, the perforated diaphragm forming an air-space at the bottom of the tank, means for establishing air-pressure in said chamber, the discharge-barrel and the plunger operating therein substantially as set forth.
11. An ore-leaching apparatus comprising the tank having a pulp-discharge, a filtering-diaphragm in said tank, means for establishing pressure below said diaphragm whereby
- to control the passage of the solution through 25 it, means by which to control the introduction of chemicals to and their withdrawal from that portion of the tank above the diaphragm, and mechanism connected with the tank whereby to extract the surplus solution from 30 the pulp discharged from the tank substantially as set forth.
12. In an ore-leaching apparatus the combination with the leaching-tank having a pulp-discharge of the conical perforated filtering- 35 hopper therein having the discharge for the pulp, means by which to maintain air-pressure below the diaphragm whereby to control the flow of solution through it, means for the introduction and withdrawal of chemicals to 40 and from the body of the tank above the filtering-diaphragm, and devices for controlling the discharge of the pulp from the tank substantially as set forth.
